Primary Examiner — Khawaja Anwar*Assistant Examiner* — Megan Tiana Rakos(74) *Attorney, Agent, or Firm* — Norton Rose Fulbright US LLP(57) **CLAIM**

The ornamental design for an intelligent gateway, as shown and described.

DESCRIPTION

FIG. 1 is a front elevation view according to a first embodiment of the present design;

FIG. 2 is a back elevation view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1;

FIG. 7 is a perspective view of FIG. 1;

FIG. 8 is another perspective view of FIG. 1;

FIG. 9 is a front elevation view according to a second embodiment of the present design;

FIG. 10 is a back elevation view of FIG. 9;

FIG. 11 is a left side view of FIG. 9;

FIG. 12 is a right side view of FIG. 9;

FIG. 13 is a top plan view of FIG. 9;

FIG. 14 is a bottom plan view of FIG. 9;

FIG. 15 is a perspective view of FIG. 9; and,

FIG. 16 is another perspective view of FIG. 9.
